TAIL STRAIGHTENER

Ray Don Hulse, New Bloomfield, Mo.

Application September 21, 1937, Serial No. 164,966
Renewed February 14, 1939

4 Claims. (Cl. 54—78)

This invention appertains to new and useful improvements in tail straighteners and more particularly to a device for correcting crooked horse tails.

5 The principal object of the present invention is to provide a device which can be readily applied to a horse's tail for the purpose of correcting any distortion thereof.

10 Another important object of the invention is to provide a tail straightener of the character stated which can be adjusted in order to correct a tail to whatever extent desired and also to relieve the horse's tail in the event of weariness on the part of the animal.

15 These and various other important objects and advantages of the invention will become apparent to the reader of the following specification.

In the drawings—

20 Figure 1 represents a rear elevational view of the device.

Figure 2 is a fragmentary horizontal sectional view taken substantially on the line 2—2 of Figure 1.

25 Figure 3 is a vertical sectional view taken substantially on the line 3—3 of Figure 1.

Figure 4 is a front elevational view of the lower end of the rest.

Figure 5 is a fragmentary plan view of one of the ring tabs.

30 Figure 6 is a sectional view taken substantially on the line 6—6 of Figure 1.

Figure 7 is a cross sectional view of one of the foundation plates.

35 Referring to the drawings wherein like numerals designate like parts, it can be seen that numerals 5—5 represent the arcuate-shaped foundation plates which are provided with a suitable thickness of padding 6 at the undersides thereof. At the rear ends of these foundation plates are 40 the strap attaching rings 7 laterally disposed, while at the forward ends of these plates 5 are the forwardly extending tabs 8 for carrying the strap attachable rings 9.

45 Numeral 10 denotes a block having the depending tongue 11 and the laterally extending pintles 12—12 which extend through openings in the bosses 13 which rise from the foundation plates.

50 5. These bosses 13 carry set screws 14 having wing heads which can be fed downwardly to bite against the pintles 12 to hold the foundation plates in proper adjusted positions on the said pintles.

55 The gripper for the horse's tail includes a plate 15 hingedly connected as at 16 to the upper portion of the tongue 11. This gripper plate 15 has

the padding 17 on the front side thereof. An adjusting screw 18 is threaded through the lower portion of the tongue 11 and is feedable against the gripper plate 15 to the extent required.

The block 10 is provided on its forward side 5 with an annular arrangement of radially disposed ratchet teeth or ribs with which the correspondingly shaped ribs on the plate 19 are engageable. Extending from the plate 19 and through an opening in the block 10 is the threaded member 10 20 which is equipped with a wing nut 21 feedable against the block 10 to hold the plate 19 and the tail rest 22 in proper adjusted position, whether it be in a straight upright position or in a laterally inclined position, depending upon the crookedness of the horse's tail.

25 The rest 22 consists of a substantially rectangular shaped frame constructed of one elongated heavy wire or rod member having its free end portions brought together as at 23 and suitably secured as by welding to the ratchet plate 19. The upper portion of this frame is bent rearwardly as at 24 and it is preferable that one or more U-shaped connecting members 25 connect the side members a—a of the frame.

30 In the event the horse appears to become weary from having his tail held in elevated and cocked position, the tail can be lowered by simply loosening the nuts 14 and permitting the rest to be lowered.

35 While the foregoing specification sets forth the invention in specific terms, it is to be understood that numerous changes in the shape, size and materials may be resorted to without departing from the spirit and scope of the invention as 35 claimed hereinafter.

Having described the invention, what is claimed as new is—

1. A tail straightener comprising a pair of foundation plates, a block, pintles extending from 40 the block, bosses on the foundation plates having openings therein for receiving the pintles, screw means on the bosses for engagement with the pintles, a tail rest vertically disposed above the block, and ratchet means between the rest and the block operative to allow lateral adjustment of the rest.

2. A tail straightener comprising a pair of foundation plates, a block, pintles extending from the block, bosses on the foundation plates having 50 openings therein for receiving the pintles, screw means on the bosses for engagement with the pintles, a tail rest vertically disposed above the block, and ratchet means between the rest and the block operative to allow lateral adjustment 55

of the rest, and a tail gripper depending from the said block.

3. A tail straightener comprising a foundation member, a tail rest, adjusting means between the tail rest and the foundation member, and adjusting means for holding the tail rest in lateral, and forward and rearward adjusted positions with respect to the foundation member.

4. A tail straightener comprising a pair of foundation plates, a block, pintles extending from

the block, bosses on the foundation plates having openings therein for receiving the pintles, screw means on the bosses for engagement with the pintles, a tail rest vertically disposed above the block, and ratchet means between the rest and the block operative to allow lateral adjustment of the rest, and an adjustable tail gripper depending from the said block. 5

ROY DON HULSE. 10
